UNITED STATES PATENT OFFICE.

JULIEN STRANDERS, OF NEW YORK, N. Y., ASSIGNOR TO HARRY B. KRUGER, OF NEW YORK, N. Y.

ADVERTISING DEVICE.

1,147,689.

Specification of Letters Patent. Patented July 20, 1915.

Application filed October 5, 1914. Serial No. 865,143.

To all whom it may concern:

Be it known that I, JULIEN STRANDERS, a subject of the King of England, and a resident of New York, borough of Brooklyn, in the State of New York, have invented certain new and useful Improvements in Advertising Devices, of which the following is a specification.

The object of this invention is to furnish an advertising device to be employed in connection with a package of the goods to be advertised so as to attract attention to the package and effectively display the same.

For this purpose, the invention comprises the advertising device composed of a unitary panel and base made of cardboard or other light material, scored at the junction of the panel and base, and having a package-receiving opening extending from the base upwardly in the panel to less than the package clearing height, whereby when the package is inserted in the opening, the panel rests in inclined position against the package, being supported thereby in upright position for effectively displaying the package.

In the accompanying drawing, Figure 1 is a perspective view of an advertising device embodying the invention; Fig. 2 is a vertical section on line 2--2, Fig. 1; Fig. 3 is a horizontal section on line 3--3, Fig. 1; Fig. 4 shows the advertising device in its blank form; and Figs. 5 and 6 are vertical sections in lines 5--5 and 6--6 respectively of Fig. 4.

Similar reference characters indicate corresponding parts in all the figures.

Referring to the drawing, the panel 10 may have any desired ornamental form, and is of greater size than the package to be displayed. The base 11 is in the blank piece 40 of cardboard from which the device is formed, unitary with the panel. The blank is scored, as indicated in Fig. 6 at 12, on the line between the panel and the base. This scoring permits the ready bending of the panel and base on the line 12, so that the base may be placed in horizontal position, as shown in Fig. 1, and indicated in dotted lines in Fig. 5, while the panel is hinged thereto on the line 12, and extends upwardly from the base. From the base, there extends upwardly in the panel an opening 13, which is of such shape as to receive the package 14 to be displayed, but which is of less height than is necessary to clear the top

of said package when the package is standing upon the base, as shown in the figures. In such case, the panel is shown in inclined position, as shown in Figs. 1 and 2. The panel is of such light weight as not to overturn the package when in such inclined position, and the combination of package and advertising device maintains its erect position with stability.

The portion of the material struck out of the opening 13 is allowed to remain attached 65 to the base as shown, and said portion 15 extends rearwardly of the base and panel when the base is placed in horizontal position, as clearly shown in the figures, thereby forming with the base a seat of uniform 70 thickness to receive the package, and said portion 15 by its connection with the base strengthening the latter and adding stability to the structure. Upon the panel may be printed, lithographed, embossed, or otherwise produced, any desired advertising information, drawing attention to the goods displayed in the opening of the panel.

The device is shown in connection with a package of canned goods, but it is obvious 80 that by alteration of the shape of the opening 13, it may be adapted to receptacles of other kinds.

Numerous changes in the construction may be made without departing from the 85 spirit of the invention, as set forth in the accompanying claims.

I claim:

1. The combination of a package and a display card, said card having a base on 90 which said package rests and a back upstanding from the base to project above the package, said back having an opening therein in which the package is received, the opening being of substantially the same height 95 as the package, whereby when the package and card are assembled the upper wall of the opening of the said back may rest on the top of the package when the back of the card is inclined.

2. An advertising device for displaying packages, comprising a unitary panel and base scored at the junction, the said panel having an opening therein, the said package being adapted to rest on the said base and 105 be received in the said opening, the opening being of substantially the same height as the package, whereby when the package is dis-

2
played the upper wall of the opening of the said panel may rest on the top of the package when the said panel is inclined.

3. An advertising device for displaying packages, comprising a combined panel and base hingedly secured at the junction thereof, the said panel having an opening therein, the said package being adapted to be received in the said opening and to rest on the said base to hold the base in supporting position, the opening being of a size to permit engagement of the package and panel with

each other, whereby when the package is displayed the wall of the opening of the said panel may rest on the package to hold the said panel in display position. 15

In testimony, that I claim the foregoing as my invention, I have signed my name in presence of two subscribing witnesses.

JULIEN STRANDERS.
